JAMES T. BOYD, M. D., OF INDIANAPOLIS, INDIANA.

Letters Patent No. 83,826, dated November 10, 1868; antedated October 31, 1868.

IMPROVEMENT IN UTERINE SUPPORTERS.

The Schedule referred to in these Letters Patent and making part of the same.

To all whom it may concern:

Be it known that I, JAMES T. BOYD, M. D., of Indianapolis, in the county of Marion, in the State of Indiana, have invented new and useful Improvements in Uterine Supporters; and I do hereby declare that the following is a full and exact description of the same, reference being had to the accompanying drawing, making part of this specification, in which—

Figure 1 represents a front view.

M M represent wires in the front pad, which wires are bent or curved in regular bends or curves, or otherwise of exact size, fitting into grooves or openings at A A, which grooves or recesses correspond in shape and size with the ends of the wires M M, so that the pad can be raised or lowered to adjust it to the size of the patient, and fastened by a button or otherwise.

B, fig. 1, represents the same arrangement of bends or curves in the end of the wire supporting the cup D, in which the neck of the uterus sits, fitting into corresponding grooves or recesses, and fastened as be-

fore, by which the stem B, with the cup D, can be raised or lowered to suit the patient.

Figure 2 represents a back view, and C C, pads, upon the back of which are coiled springs or wires, by which the instrument can be enlarged by uncoiling, and contracted by coiling up, so as to suit the size of the person.

What I claim as new in my invention, and desire to secure by Letters Patent, is—

The curved wires M M and B, and their corresponding grooves in the pad A A, with their fastenings and attachments, in the manner and for the purpose substantially as set forth.

Also, the coiled springs or wires on the back of the pads C C, arranged and attached in the manner and for the purpose substantially as set forth.

J. T. BOYD, M. D.
